United States Patent Office

Des. 192,826
Patented May 15, 1962

192,826

DECANTER

Ernest L. Du Pree, New York, N.Y., assignor to Schenley
Industries, Inc., New York, N.Y., a corporation of Delaware

Filed Aug. 18, 1961, Ser. No. 66,420

Term of patent 14 years

(Cl. D58—6)

1

I claim:

The ornamental design for a decanter, as shown and described.
